UNITED STATES PATENT OFFICE.

JOHN O. ROLLINS, OF FRESNO, CALIFORNIA.

GRINDING-MACHINE.

1,381,593.

Specification of Letters Patent. Patented June 14, 1921.

Application filed May 13, 1920. Serial No. 381,054.

To all whom it may concern:

Be it known that I, JOHN O. ROLLINS, a citizen of Switzerland, residing at Berkeley Hotel, in the city of Fresno, county of Fresno, and State of California, have invented new and useful Improvements in Grinding-Machines, of which the following is a specification.

The present invention relates to a grinding machine and has reference more particularly to a machine for grinding the beveled surface on the disk shaped heads of puppet valves used on internal combustion engines.

The primary object of the invention is to provide a self contained, so to speak, valve grinding outfit which will enable any one regardless of their mechanical skill or the machine shop equipment available to effect the proper grinding or cleaning of valves or the like.

The preferred embodiment of the invention is illustrated in the accompanying drawing and will be referred to as an illustrative example in the following detailed description:

In said drawing: Figure 1 is a plan view of the machine showing co-operative relationship of the parts, and with the valve carried thereby in the act of being ground.

Fig. 2 is a side elevation of the machine.

Referring now to the drawings in detail, the idea in its present form contemplates practically a one piece supporting base on which the operative parts of the machine are installed. This base primarily consists in a mounting 1 for the motor 2, the same being directly supported by a sub-base 3 which in turn is mounted in the block 4 which block is mounted upon the base 1.

The sub-base 3 preferably comprises a cross slide having beveled marginal edges and received by the cross slot 5 in the block 4 so that the motor is capable of a lateral sliding adjustment. To effect a fixed position of the motor 2 on the block 4, suitable set screws 6 are presented through the end of the block with their ends made to engage a side of the sub-base 3. The block 4 is adapted to have a sliding movement on the base 1 longitudinally of the axis of the motor. To realize this adjustment the block 1 is provided with tracks or the like 7 spaced apart and made to be received in suitable elongated slots arranged longitudinally in the block 4.

A screw 8 having a bearing 9 fixed to the end 55 of the base 1 and having a threaded engagement with an opening made to receive it in the block 4 is adapted to be manipulated by the handle 10 to which it is attached for running the block 4 longitudinally on the base 1 60 and carrying with it the motor 2 on which it is supported. With this construction, it will be readily seen that a lateral or longitudinal adjustment of the motor 2 may be 65 readily effected.

The motor 2 is provided with the customary shaft 11 on the end of which is keyed the grinding wheel 12. The lateral or longitudinal adjustment of the motor above described is rendered possible so that the position of the wheel 12 may be regulated as occasion demands. The base 1 at the front of the motor extends to a plane higher than that part which supports the motor and terminates in a relatively long or oblong 75 shaped support 13 for supporting the oblong shaped base 14 of the work holder. This base 14 is pivoted to the base 13 as at 15 so that the base 14, while being held against longitudinal movement is capable of being 80 swung around the pivot 15. To control and also limit the swinging movement of the base 14, the base 13 is recessed to provide relatively long slots 16 at opposite ends of the base. Suitable thumb screws 17 are 85 adapted to be passed through these slots with a threaded engagement with the chuck head 18 of the work holder and the mounting or tail stock 19 for the centering pin 20. 21 represents the stem of an ordinary puppet 90 valve having the usual disk shaped head 22 with the customary beveled surface shown at 23. Inasmuch as it is this beveled surface desired to be cleaned and ground, the valve stem 21 is supported by the chuck 24 with the 95 disk shaped head 22 centered by the bolt 20 so that the valve stem 21 may be rotated by the shaft on which the chuck 24 is mounted. 25 represents an end abutment for the shaft.

In order to present the beveled surface 23 100 of the valve head to the wheel 12 at the proper angle for grinding, the work holder or rather the mounting for the chuck which carries the valve is presented to the wheel 12 at an oblique angle, so that the bevel on the 105 valve head will be presented parallel with the axis of the wheel 12. Of course by means of the thumb screws 17 and the

pivotal mounting of the base 14, any variation of this adjustment may be accomplished. Furthermore with the manner of mounting the motor 2, the relative position 5 of the wheel 12 and the disk shaped head of the valve may be changed. To rotate the valve in the work holder, a drive is imparted from the shaft 11 of the motor. It is established by a belt from the shaft 11 to 10 the pulley 26 which is supported by the arm 27 and the bearings 28. The arm 27 being fixed to the block 4 and inasmuch as the pulley 26 is supported on the arm, the distance between it and the shaft will be 15 changed when the motor 2 is laterally adjusted. Consequently, the belt from the shaft 11 to the roller 26 should be of rubber or some other resilient material. The pulley 26 is keyed to a collar 29 made to receive 20 one end of a flexible driving shaft 30 the other end of the shaft being received in a similar collar 31 which is fixed to the pulley 32 which in turn is supported by means of the arm 33 working in suitable bearings 25 as at 34. The pulley 32 is presented parallel with a pulley 35 mounted upon and keyed to shaft 25. With a belt connecting the pulleys 32 and 35, it will readily be seen how the necessary rotation may be imparted 30 to the valve stem 21 through the shaft 25 which is in driving relation with the belt connecting the pulleys 32 and 35 through the flexible drive shaft 30 and the belting connecting the shaft 11 and the pulley 26. 35 In supporting the valve in the work holder the end of the stem is of course received by the chuck 24 and the center pin 20 is turned upon until a tension is felt on the spring 36, which is confined between the 40 end of the shaft 25 and the housing 37. The subbase 3 of the motor 2 is then moved until the wheel 12 is in close proximity to the beveled surface 23 of the valve. Then the center pin 20 is again moved up to impart a thrust or movement of the valve against the influence of the spring 36 until the beveled surface 23 bears against the wheel 12. The adjustments all made and 45 movable parts are locked together and the motor started whereupon the grinding action will start. By means of the handle 10 and the screw 8 the wheel may be moved across the beveled surface of the valve head should occasion demand.

I claim:

1. A grinding machine having in combination a work holder, a base on which the work holder is mounted, a grinding wheel, means for driving the same, a movable base on which the grinding wheel is mounted, a 55 flexible drive established from the means for driving the grinding wheel to the work holder, means for effecting a lateral and longitudinal adjustment of the grinding wheel through its movable base, and means 60 for effecting an adjustment of the work holder relative to the grinding wheel.

2. In a machine for grinding the beveled surface of the disk shaped heads of puppet valves comprising a grinding wheel, a motor 70 for driving the said wheel having a shaft on which the wheel is mounted, a base for supporting said motor having means for effecting a lateral or longitudinal adjustment of the motor with the grinding wheel 75 carried thereby, a work holder supporting the valve with the beveled surface thereof, presented parallel to the axis of the grinding wheel, means for changing the angle of inclination of the valve relative to the 80 grinding wheel, and means for effecting a contact with the beveled surface of the valve head with the wheel under spring tension with means for adjusting said tension.

3. In a machine of the class described, a 85 motor having a driving shaft, a grinding wheel on said shaft and adapted to be driven thereby, a support for the motor including a main base movable in a horizontal plane parallel to the driving shaft of the 90 motor, a sub-base upon which the motor is directly supported, said sub-base being mounted upon the main base and movable thereon in a horizontal plane transverse to the driving shaft of the motor; and a work 95 holder, for supporting the work in contact with the grinding wheel and at an angle to the axis of rotation thereof, and means for changing the horizontal angular position of the work holder.

4. A machine of the class described and as set forth in claim 3 and in which the work is adapted to be supported on the work holder in grinding contact with the grinding wheel under spring tension with 105 means for changing the effective tension of said spring tension means.

JOHN O. ROLLINS.
